UNITED STATES PATENT OFFICE.

FRANK M. BUTLER, OF ELKO, NEVADA.

VALVE-SPRING LIFTER.

Application filed April 27, 1920. Serial No. 376,640.

To all whom it may concern:

Be it known that I, FRANK M. BUTLER, a citizen of the United States, residing at Elko, in the county of Elko and State of Nevada, have invented certain new and useful Improvement in Valve-Spring Lifters, of which the following is a specification, reference being had therein to the accompanying drawing.

10 This invention relates to valve lifters and has for its principal object the provision of a device of this character adapted for lifting the valve spring for removing the cross pin, for raising the valve to remove the same, 15 and for removing the valve spring.

Another object resides in the provision of means for holding the jaws of the lifter either in closed or open position.

With these and other objects in view, my 20 invention consists in the novel details of construction and arrangement of parts which will be more clearly understood from the following specification and drawings, in which:—

25 Figure 1 is a side elevation showing the initial position of the valve lifter.

Figure 2 is a side elevation of the valve lifter showing the spring pressed for removal of the cross pin.

30 Figure 3 is a top plan view of the valve lifter.

Figure 4 is a detail perspective of the jaws of the valve lifter.

In carrying out my invention I provide 35 the levers A and B which are pivotally connected at 1. The lever A is curved as shown and at one end is provided with a bifurcated jaw 2, the under side of which is provided with teeth or corrugations 3. The opposite end of this lever A is formed with the right angle extensions 4 for a purpose to be later described.

The lever B is curved, as shown, to provide a recess or concaved portion at 5, adjacent the pivot point 1. One end of this lever B is provided with a bifurcated jaw 6, the upper face of which is provided with the teeth or corrugations 7. The opposite end of this lever is provided with the right angle extension 8, adapted to cooperate with the extension 4 on the lever A for a purpose to be later described. The ends of the levers having the right angle extensions are slightly offset towards one another, as shown at 9, so that the end of the lever B will overlie

the end of the lever A. The end of the lever B having the bifurcated jaw is also slightly curved, as shown at 10 and offset so that the jaw 6 will overlie the jaw 2 of the lever A.

60 A ring 11 encircles the levers and will normally rest in the recess 5 formed in the lever B. This ring may be slid in either direction on the levers and if towards the jaws will hold the jaws in closed position, while if towards the opposite ends will hold the jaws in open position. The jaws 2 and 6 will prevent the ring from sliding off one end of the levers whereas the right angle extensions 4 and 8 will prevent it from sliding off the 70 opposite end.

When in use the bifurcated jaws 2 and 6 will be brought together and forced between the casting 12 and the plate 13 carried on the valve stem 14. Then by pressing on the 75 opposite ends of the levers, the jaw 6 will be raised and will compress the coiled spring 15 surrounding the valve stem 14. When the spring has been compressed to the desired point the ring 11 will be slid towards 80 the ends of the levers having the right angle extensions 4 and 8 and will hold the jaws open so that the cross pin 16 may be removed from the valve stem. After the pin has been removed the ring 11 is again slid 85 into the recess 5 and the spring 15 is allowed to expand and carry the plate 13 downwardly on the jaw 6. When in its lowermost position the plate 13 will engage under the end of the valve stem 14 and then by 90 again operating the levers to recompress the spring, the valve 17 will be raised and can be removed. After the valve has been removed the spring will again be allowed to expand and by slightly tilting the levers the 95 spring may be removed.

From the above detailed description it will be seen that I have provided a tool which may be used for lifting the valve spring for removing the cross pin from the 100 stem, for removing the valve, and for removing the spring. It will also be noted that means have been provided for holding the jaws either in closed or open position so that the hands of the user will be free for 105 removing the cross pin, valve, or spring. By having the ends of the levers offset, as shown at 9, the movement of the levers will be limited and it will be impossible for the end of the lever B to pass the end of the 110

2
lever A. By curving and offsetting the opposite end of the lever B, the jaw will overlie the jaw of the lever A. Particular stress is laid on the provision of the recessed or concaved portion 5 in the lever B which allows the ring 11 to be so held, when not in use, as not to interfere with the manipulation of the levers. The teeth or corrugations on the jaws will allow the jaws to have

10 a more secure grip.

While I have described the preferred form of my invention, it will be understood that minor changes may be made in the construction without departing from the spirit

15 of the invention.

Having fully described my invention, what I claim as new and desire to secure by Letters Patent is:—

1. A valve lifter comprising two levers 20 pivotally connected intermediate their ends, one of said levers being curved upwardly towards each end, from the pivot point, to form a recess adjacent the pivot, and a ring

normally received in the recess but adapted to be slid towards either end of the levers. 25

2. A valve lifter comprising two levers pivotally connected intermediate their ends, one of said levers being curved upwardly towards each end, from the pivot point, to form a recess adjacent the pivot, an enlarged bifurcated portion on adjacent ends of each lever, an outwardly extending projection formed on the opposite ends of the levers, a ring normally received in the recess but adapted to be slid towards either end of the levers, the 35 movement of said ring being limited in one direction by the bifurcated enlarged ends and in the opposite direction by the outwardly extending projections.

In testimony whereof I hereunto affix my 40 signature in the presence of two witnesses.

FRANK M. BUTLER.
